UNITED STATES PATENT OFFICE.

JULIEN STRANDERS, OF NEW YORK, N. Y., ASSIGNOR TO THE SEITER & KAPPES LITHOGRAPHING CO., OF NEW YORK, N. Y., A CORPORATION OF NEW YORK.

DISPLAY DEVICE.

1,075,069.

Specification of Letters Patent.

Patented Oct. 7, 1913.

Application filed October 31, 1912. Serial No. 728,833.

To all whom it may concern:

Be it known that I, JULIEN STRANDERS, a subject of the King of Great Britain, residing in New York, in the borough of Brooklyn, county of Kings, and State of New York, have invented certain new and useful Improvements in Display Devices, of which the following is a specification.

The invention relates to an improved display-device which is intended for advertising various articles of merchandise, such as tobacco, cigars, candies and the like, in a very effective manner when placed in the show-windows of stores, on the counters and other exposed points, but which can be readily folded up into flat shape for convenience of shipping and readily put up for use at the points required; and for this purpose the invention consists of a display-device which will be further described hereinafter and finally pointed out in the claims.

In the accompanying drawing, Figure 1 represents a perspective view of my improved display-device, Fig. 2 is a vertical transverse section on line 2, 2, Fig. 1, Fig. 3 is a front-elevation of the display-device, shown folded up for shipment. Figs. 4 and 5 are respectively horizontal sections on lines 4, 4, Fig. 1, and 5, 5, Fig. 3, and Fig. 6 is a vertical transverse section on line 6, 6, Fig. 3.

Similar letters of reference indicate corresponding parts throughout the different figures of the drawing.

Referring to the drawing, *a* represents the main-piece of my improved display-device, which is made preferably rectangular at its lower part and provided with an extension *a*¹ at its upper part, said extension being made in the shape of a human head. The main-piece *a*, *a*¹ is preferably made of pasteboard or other suitable material and printed in colors so as to simulate the head of a smoker, candy-eater or other person, according to the merchandise that is to be advertised by the display-device. The main-piece *a* is supported in upright position by a stay *b* of approximately triangular shape, which is placed at right angles to the main-piece *a*, and which is connected thereto by means of a vertical slit *b*¹ that extends from the upper portion of the stay to some distance in downward direction in the same and interlocks with a vertical slit *a*² which extends in the main-piece from the lower

part to some distance in upward direction. The front-portion *b*² of the stay *b* is made with an inclined edge, as shown in Fig. 2, and supports a piece *d* of pasteboard, which is made in the shape of an arm and hand holding a pipe when the display-device advertises tobacco, cigars and other like articles, the inclined piece *d* being connected by a paper or muslin hinge with the front-portion *b*² of the stay *b* and provided at its upper end with a tapering extension or tongue *d*¹. The tapering tongue *d*¹ is inserted into a slot *a*⁴ in the main-piece and into a recess *b*³ provided for the end of the tongue *d*¹ in the upper portion of the stay *b*, the inclined piece *d* giving thereby the impression of a pipe, cigar or other article held in the hand of the person represented and having its end inserted into the mouth of the same. On the upper portion *a*¹ of the main-piece *a* is arranged in an inclined position a disk or other shaped top-piece *e*, which rests on shoulders *a*⁵ of the upper portion *a*¹ and which is provided with a transverse slit *e*¹ for being placed over the upper portion *a*¹, and in its rear-part with a short longitudinal slit *e*² that is located at right angles to the transverse slit *e*¹ and by which the top-piece *e*, which is intended to represent the brim of a hat, is adapted to be placed in locking connection with a lug *b*⁴ at the upper inclined rear-portion of the stay *b*, as shown clearly in Figs. 1 and 2. When the display-device is in position for use, the stay is placed at right angles to the main-piece, the upper tongue-shaped end of the holding piece *d* inserted into the slit *a*² in the main-piece and recess in the stay, and the inclined top-piece placed into locking connection with the lug of the rear-portion of the stay, whereby the display-device imparts a very effective and striking impression.

The available space on the main piece is utilized for representations of the article to be advertised, the name or brand of the article, and similar advertising matter.

When the display-device is to be packed for shipment, the stay is turned over so that its front and rear portions are placed flat against the main-piece, which brings the inclined holding piece with its tongue flat over the stay, as shown in Figs. 3 and 5, while the top-piece is unlocked from the lug of the rear-portion of the stay and folded

partly over the stay and partly over the upper front-portion of the main-piece, taking up thereby very little space for packing and shipment.

5. The very impressive and striking appearance of the display-device adapts the same in a high degree for advertising different articles of manufacture, especially as the display-device can be shipped in flat state 10 to the exhibitor and then put up in the show-window, etc., by placing the parts in proper interlocking position with each other.

I claim:

1. A display-device, comprising a main-piece, a stay having an inclined front-portion, said main-piece and stay being connected by means of interlocking slits respectively in their upper and lower parts, a holding piece hinged to the inclined front-portion of the stay, a top-piece applied to the upper part of the main-piece, and means for interlocking the holding piece and the top-piece with the main-piece and stay.

2. A display-device, comprising a main-piece, a stay composed of an inclined front-portion and a higher rear-portion, said main-piece and stay being provided with interlocking slits for being placed at right angles to each other or in folded position adjacent 30 to each other, a holding piece hinged to the inclined front-portion of the stay and provided with a tongue extending through a slit in the upper front-portion of the main-piece and into a recess in the stay, and a top-piece having a transverse slit for being placed over the upper portion of the main-piece, and means for interlocking said top-piece with the upper rear-portion of the stay.

40 3. A display-device, comprising a main-piece, a stay interlocking by slits with the main-piece, said stay being formed of a rear-portion having a recess and a lug at its upper end, and a front-portion having an inclined edge, a holding piece hinged to the inclined edge of the front-portion of the stay and provided with a tongue extending through a slit of the main-piece into the recess of the rear-portion of the stay, and a 45 top-piece provided with a transverse slit fitting over the upper end of the main-piece and a longitudinal slit interlocking with the lug of the rear-portion of the stay.

4. A display-device, comprising a main-

piece having an upper portion of reduced width provided with shoulders, a stay for supporting said main-piece, a top-piece resting on said upper portion and provided with a transverse slit, and means for locking the top-piece to the upper end of the stay. 55 60

5. A display-device, comprising a main-piece having an upper portion of reduced width provided with shoulders, a stay for supporting said main-piece and provided with a locking lug at the upper end, a top-piece resting on said shoulders and provided with a transverse slit and a rear-slit at right angles to the transverse slit and adapted to interlock with the lug on the stay. 65

6. In a display device, the combination of a main-piece, a stay for supporting the same adapted to be placed in supporting position to the main-piece, and a top-piece engaged by the upper portion of the main-piece and extending forwardly of the main-piece, and with a locking device engaged by the stay when the stay is placed in supporting position. 70

7. In a display device, the combination of a main-piece, provided with a slit, a stay 80 provided with a slit hingeably connected with the main-piece by the unslotted portions engaging the slotted portions, said stay extending to the front and to the rear of the main-piece, and an auxiliary piece in front of the main-piece held in extended position by the stay, when substantially at right angles to the main-piece. 85

8. In a display device, the combination of a main-piece, an auxiliary piece in front of 90 the same, and a stay between the same and the main-piece, extending also rearwardly of the main-piece, and a top piece for engaging both the stay and main-piece for holding them in extended position. 95

9. In a display device, the combination of a main-piece, an auxiliary piece in front of the same, and a stay between the same and the main-piece extending rearwardly of the main-piece to act as a supporting device 100 therefor.

In testimony, that I claim the foregoing as my invention, I have signed my name in presence of two subscribing witnesses.

JULIEN STRANDERS.
